UNITED STATES PATENT OFFICE.

GARDNER L. HOLT, OF HARTFORD, CONNECTICUT.

AWL.

No. 829,154.

Specification of Letters Patent.

Patented Aug. 21, 1906.

Application filed February 8, 1906. Serial No. 300,062.

To all whom it may concern:

Be it known that I, GARDNER L. HOLT, of the city and county of Hartford and State of Connecticut, have invented certain new and useful Improvements in Awls, which improvements are described in the following specification and are illustrated by the accompanying drawings.

My invention relates to awls and similar tools in general and to brad-awls in particular.

It is the object and purpose of the invention to produce between the blade and handle of such an implement a firm and reliable engagement which will permit a ready assembling and disassembling of the parts of the tool with a view to the removal and substitution of interchangeable blades as breakage, wear, or changing use may suggest. To accomplish this object, I use a tapering split sleeve which engages the shank of the blade in a peculiar manner and is fastened into the handle of the tool while so engaging that blade.

The accompanying drawings show the best manner in which I have contemplated applying the principles of the invention.

Figure 1 is a partly sectional side elevation of a brad-awl which is constructed in accordance with those principles. Fig. 2 is an enlarged cross-sectional view of the same brad-awl on section-line 2 2 of Fig. 1. Fig. 3 is an axial section of such brad-awl in a modified form. Fig. 4 is a cross-section on section-line 4 4 of Fig. 3. Fig. 5 is a detail.

In the drawings the numeral 1 denotes the awl-handle, which is made of wood or other slightly-elastic material, is of any ordinary or convenient form, and is provided in the usual manner with a ferrule 3 and an axial bore 5. The blade of the awl is denoted by the numeral 6. It consists of a pointed steel rod provided with feathers 7, struck out on opposite sides of the blade-shank. Blade 6 has an externally-tapering sleeve or bushing 10, having a pair of internal sockets 9, which are occupied by said feathers 7, as shown. This tapering sleeve being split in an axial plane consists of two equal similar contiguous separable half-sleeves 10, inclosing between them the shank of blade 6. Fig. 5 is a separate view of one of these two half-sleeves. The chamber 11 of sleeve 10 terminates within that sleeve, as shown in Figs. 1, 3, and 5, and leaves that member solid, as an abutment, behind blade 6. Near its smaller end

the same tapering sleeve is made flat on opposite sides parallel to said axial plane, as shown in Figs. 1 and 2 and 4. In its middle and larger portion the same sleeve is externally hexagonal or otherwise angular in cross-section, as shown in Figs. 2 and 4. At its forward end it has a head 12 of general cylindrical form, which is a trifle larger than the opening through ferrule 3 into the handle-bore 5.

In that modification of my invention which is shown in Figs. 3 and 4 each socket 9 instead of being formed as in Figs. 1, 2, and 5 wholly within a single half-sleeve 10 is formed partly in each of two such half-sleeves contiguous to each other. In that case the feathers 7 lie between the two halves of sleeves 10.

To assemble the tool which is above described, the blade 6 is first inserted between the separable halves of sleeve 10 in such a position that the shank of that blade reaches to the bottom or inner end of chamber 11, while feathers 7 occupy their respective sockets 9. Then the tapering sleeve is forcibly driven into handle-bore 5 until its two half-sleeves 10 are wedged firmly together in that bore and until head 12 in the effort to enter the orifice of ferrule 3 has introverted the edges of that orifice, as shown in Figs. 1 and 3, and has compressed the yielding material of the handle against sleeve 8 within and behind that ferrule. Then a hole 13 is drilled through handle 1 and the flattened shanks of half-sleeves 10 continuously, as shown in Figs. 1 and 3. A cross-pin 14 is then inserted removably in hole 13. To disassemble the awl, the pin 14 is first withdrawn from hole 13. Then sleeve 10 is seized by its head 12 and forcibly drawn out of the handle. Thereupon the separable halves of that sleeve fall apart and are ready to take a new or interchangeable blade 6 and to be reassembled in the handle as before.

Such being the construction and manipulation of my improved brad-awls and similar tools, the mode of operation of the same involves certain mechanical advantages which will now be pointed out. As the cross-pin 14 and the external angles of sleeve 10 separately as well as conjointly resist all twisting of that sleeve in handle 1 and as feathers 7, seated in sockets 9, resist all rotatory turning of blade 6 in that sleeve, it results that all twisting of the blade in the handle is effectually prevented by the cooperative action of

said sleeve-angles, cross-pin, shank-feathers, and sleeve-sockets, and, similarly, as ferrule 3, head 12, and pin 14 conjointly resist the backward thrust of sleeve 10 in handle 1 and as feathers 7, inclosed in sockets 9, and the solid abutment in the sleeve 10 conjointly resist all backward thrust of blade 6 in sleeve 10 it results that all backward drive of blade 6 in handle 1 is effectually prevented by the 10 coöperative action of said ferrule, head, pin, feathers, sockets, and abutment.

Such being the construction and mode of internal operation of my improved brad-awls and similar tools, I claim as my invention—

15 1. In a brad-awl, or similar tool, having a wooden handle, which is provided with an axial bore and a metallic ferrule, a blade, which is provided with projecting feathers, in combination with an angular, tapering, split 20 sleeve, which is provided with internal sockets, containing said feathers, incloses the shank of said blade, has an internal abutment, stopping said blade, and an enlarged head

engaging said ferrule, and is driven into said axial bore and removably pinned to said 25 handle.

2. In a brad-awl, or similar tool, an axially-bored handle, of wood or like material, and a blade which has a feathered shank, in combination with an intermediate split and 30 tapering sleeve, which hugs said feathered shank, and is driven into said handle, and pinned together therein.

3. In a brad-awl, or similar tool, a feathered blade, and a bored handle, in combination with an intermediate split sleeve, which hugs the feathered blade, and is both held together and fastened non-rotatably in its position in the handle by means of a pin through both sleeve and handle.

In testimony whereof I hereunto set my name in the presence of two witnesses.

GARDNER L. HOLT.
